UNITED STATES PATENT OFFICE.

WILLIAM H. CANNARD AND ALEXANDER W. WITBRO, OF GREEN BAY, WISCONSIN.

TOILET KIT OR CONTAINER.

Application filed June 12, 1926. Serial No. 115,514.

This invention primarily relates to toilet kits or containers for toilet materials and an accessorial element including, in this instance, a pack of interfolded sheets of paper or the like.

The primary object of our inventive-concept is to aggroup, in a suitable container—such as the compact now much in vogue and other types of containers—certain materials, such as powder, and an applying element, such as paper or the like, whereby the user may have at hand not only face powder (for example) but also an element (such as a sheet of paper) for applying the powder. It is a well-known fact that powder-puffs and the like, now extensively used, are more or less unsanitary. It is, of course, practically out of the question to provide a puff for each application; but our inventive-concept provides for just that sort of thing.

The invention comprises any appropriate type of compact or receptacle in which provision is made for a toilet element—which may either be face powder, talc, rouge, or the like—and, in convenient and aggrouped relation thereto, the aforementioned applying element, this being preferably one of a series of paper sheets which may be interfolded to facilitate dispensing thereof when the user desires to apply the powder, for instance, to the face. To that end, the structure comprises a container of any required type and form, and which includes a box-component and a closure-component there being associated with one or the other of these components a powder-compartment and, also, a paper-compartment. In a more specific embodiment, the structure contemplates a box-component to which is hinged a closure or cover-component; the box-component being provided with a paper-compartment and means for facilitating the dispensing of the contents thereof; the closure-component including a compartment for powder of any appropriate kind, rouge, or other types of toilet articles. Associated with these instrumentalities is, preferably, a mirror adapted to be used during the application of the toilet article by the paper-element.

Where we have herein used the term "powder" or equivalent terms, it is to be understood that such terms comprehend face, toilet and other kinds of powder, rouge, etc., in loose or solid form.

In order that the invention may be more

readily comprehended, we have herein revealed the same in three embodiments; but it is to be understood that these are merely illustrative, that other embodiments and utilizations are possible, and that the particular embodiments disclosed are susceptible of a wide range of variation and modification without departing from the spirit of the invention or sacrificing any of its underlying principles or salient features.

In these drawings:

Figure 1 is a view in perspective of a compact or toilet kit with our inventive-concept incorporated therein;

Figure 2 is a view in transverse, vertical section, on the line 2—2, Fig. 1;

Figure 3 is a fragmentary view, in section, of retaining means for the closure of the box-component and of the paper-compartment;

Figure 4 is a view in elevation of another embodiment, being in this instance a box for containing toilet powder, and provided with an integral paper-compartment;

Figure 5 is a view in horizontal section, on the line 5—5, Fig. 4;

Figure 6 is a view in elevation of a third embodiment, being also a box for toilet powder but with the paper-compartment associated therewith as an attachment; and

Figure 7 is a view in horizontal section, on the line 7—7, Fig. 6.

Referring to the drawings, the reference-character 1 designates a receptacle or box-component shown, in this instance, as rectangular in form and constructed of any suitable material, such as metal. This receptacle includes a bottom-portion 2, a front-portion 3, a back-portion 4 and side-portions 5. These portions may be made by any well known stamping method.

Associated with the box-component is a closure or cover-component 6 comprising, in this instance, a top-portion 7, a front-portion 8, a back-portion 9, and side-portions 10. The closure-component 6 is, preferably and as shown, connected to the back-portion 4 of the box-component by hinges 11.

The cover 6 is divided into compartments 12 and 13, respectively, the compartment 12 containing a toilet article 14, which may be powder or other form of toilet element. In the compartment 13 is a mirror 15, this being in immediate and convenient association with the powder-compact 14.

The front, back and side walls or portions

of the box-compartment 2 provide a compartment 16 in which, in this instance, is disposed a pack of sheets of paper or the like, adapted to be dispensed for applying the material of the compact 14 and to facilitate which the mirror 15 is used. The paper, in this instance, is preferably interfolded to facilitate its withdrawal, sheet by sheet, from the compartment 16. It is to be understood that instead of paper, other suitable applying material may be used, such as fabric.

Overlying the paper-pack 17 is a closure-component 18 constituting, in this instance, a covering for the paper-compartment 16. This component comprises a top-portion 19, a front-portion or wall 20, a back-portion or wall 21, and side-portions or walls 22, and which several portions or walls are made by flanging the top-portion 19 of the component. To facilitate the positioning of the component with respect to its compartment, the cover 18 is secured to the hinges 11, as shown. Thus, these hinges are common to both closures 7 and 18. The flanges or walls of the component engage the respective walls or portions of the box-compartment, as shown.

The closure 18 is provided with a longitudinal slot or aperture 23 through which a sheet 24 of the paper-pack 17 normally extends to facilitate withdrawal of the sheets successively from time to time. The closure is more or less skeletonized by being formed with cut-outs 25, 25.

In order to retain the closure 18 in normal, closed position, the front wall 3 of the box-compartment is formed with an indentation 26 adapted to register with a depression 28 in the front wall 20 of the closure 18. To hold the closure 7 in closed position with relation to the box-component, it is provided with a pendent lug 27 provided with an indentation 28' adapted to coact with the indentation in the wall 3. Thus, the front walls of the closures 8 and 18 and the front wall of the box-component have associated retaining means for holding both closures in their lowered position.

The structure thus provided constitutes a compact or receptacle of convenient dimensions, with various instrumentalities aggrouped for convenience. To dispense the paper-pack 17 in the paper-compartment 16, the closure 18 is raised to the position, say, indicated in dotted lines in Fig. 2, after which it is re-positioned with one of the sheets 24 projecting through the aperture 23. By reason of the interfolding of the series of sheets, the pulling of one through the aperture 23 draws the next succeeding sheet therethrough and in position for use.

Referring, now, to the embodiment illustrated in Fig. 4, it will be found to include a box-component 29 in which is formed a powder-compartment 30, the discharge of

contents from which is controlled by a closure-component 31, of usual type, movably mounted on the box-component. Formed integral, in this instance, with the box-component is a paper-compartment 32 provided with a central, vertical opening or aperture 33 through which a sheet 34 from a pack 35 of interfolded sheets is withdrawn. It will be understood that, in this instance, the paper sheets are inserted into the compartment 32 through an opening 36 at the top of the compartment 32. It will also be noted that, in this embodiment, as well as in the one illustrated in Figs. 1 to 3, there is a container for a toilet article and an accessory element, including a box-component comprising a powder-compartment, and a closure-component movably mounted on the box-component.

In the embodiment illustrated in Fig. 6, the paper-compartment is shown as non-integral with the container. In this instance, a box-component 37 includes a powder-compartment 38, the discharge of which is controlled by a closure 39 movably mounted on the box-component. To provide for holding a pack of paper or the like an encompassing element 40 is disposed on the box-component and, this being spaced from the latter at the front, provides a paper-compartment 41, the contents of which are dispensed through an aperture 42, in the same manner as described in respect to the embodiments of Figs. 4 and 5. To retain the encompassing element 40 in position on the box-component, it is provided at its upper portion with an extension 43 formed with an aperture 44 adapted to encircle the neck 45 of the closure 39. At the bottom, the encompassing element 40 is provided with a holding piece 46 contacting with the bottom of the box-compartment and bent upward at the back opposite the aperture 42 to provide an upstanding extension 47.

From the foregoing, it will be understood that, in these several embodiments, we have provided, in a conveniently combined form, and as a part of or in association with, a compartment for holding toilet articles such as powder and the like, a paper-compartment adapted to hold a pack of interfolded sheets that can readily be dispensed from the compartment and used in conjunction with the powder, etc., of the other compartment.

What we claim is:

1. A container for powder and an accessory element, including a box-component, a closure-component therefor, a powder-compartment within the container, for mounting a body of powder and an elongated paper-compartment for housing a package of separable sheets, said compartment being combinatively associated with the container and relatively remote from the powder-compartment and having an aperture for withdrawal

of the contents of the compartment; whereby a sheet of paper may be removed at will from the container and access to the powder also facilitated.

5 2. A container for a toilet article and an
accessorial element, including a box-component,
a closure-component therefor, a toilet
article compartment within the container and
protected by the closure-component, a paper-
10 compartment combinatively associated with
the container and one wall of which con-
stitutes a wall of the box-component, and
means for guiding withdrawal of paper from
the compartment.

15 3. A container for a toilet article and an
accessorial element, including a box-component,
a closure-component therefor, a toilet
article compartment within the container
and protected by the closure-component, and
20 a paper-compartment combinatively associ-
ated with the container and one wall of which
constitutes a wall of the box-component, an-
other wall of the compartment being aper-
tured to facilitate withdrawal of paper there-
from.

4. A container for powder and the like, including an accessory powder applying-element, comprising a box-component, a closure-component therefor movably connected 30 to the box-component, a powder-compartment within the container for mounting a body of powder separately from the applying element, and a paper-compartment for housing a package of separable paper sheets, 35 said compartment being combinatively associated with the container and provided with a paper-discharging opening, the closure-component being separable from the paper-compartment for introduction thereto of its 40 contents.

40 5. A container for toilet powder and an
accessorial applying-element, including a
box-component, a closure therefor hingedly
connected thereto, a powder-compartment in
45 the closure-component, a paper-compartment
in the box-component for housing separable
paper sheets, a closure for that compartment
hingedly connected to the box-component and
apertured longitudinally to dispense, success-
50 sively, sheets of said paper from the compart-
ment for use in conjunction with powder
from the powder-compartment the two clo-
sures being independently movable, and a
mirror in the closure-component and juxta-
55 posed to the powder-compartment and over-
lying the closure for the paper-compartment
when the container is closed.

6. A container for toilet powder and an
accessorial applying-element, including a
60 box-component, a closure therefor hingedly
connected thereto, a powder-compartment in
the closure-component, a paper-compartment
in the box-component, a closure for that com-
partment hingedly connected to the box-com-
65 ponent and apertured longitudinally to dis-

pense paper from the compartment for use in conjunction with powder from the powder-compartment, said closure being flanged at its edges to guide it into the box-component, and a mirror in the closure-component and juxtaposed to the powder-compartment and overlying the closure for the paper-compartment when the container is closed. 70

7. A container for toilet powder and an accessory applying-element, including a box-component, a closure therefor hingedly connected thereto, a powder-compartment in the closure-component, a paper-compartment in the box-component, a closure for that compartment hingedly connected to the box-component and apertured longitudinally to dispense paper from the compartment for use in conjunction with powder from the powder-compartment, said closure being flanged at its edges to guide it into the box-component, the two closures being independently movable whereby the container may be opened without disturbing the paper-compartment while its closure may be raised after the closure of the box-component has been elevated 80 a mirror in the closure-component and juxtaposed to the powder-compartment and overlying the closure for the paper-compartment when the container is closed, and coacting means between the box-component and the paper-compartment for retaining the closures in a closed position. 85 90 95

8. A container for powder and an accessory element, including a box-component, 100 a closure-component therefor, a powder-compartment within the container, a paper-compartment associated with the container, a package of interfolded paper sheets within the paper-compartment and underlying the powder-compartment when the closure-component is in closed position, the latter operating protectively to hold the sheets within the compartment, and a body of powder in the powder-compartment and separated from the paper by the closure for the paper-compartment. 105 110

9. A container for toilet powder and an accessory applying element, including a box-component, a closure therefor hingedly connected thereto, a cover-component, a paper-compartment in one of said components, a closure for that compartment hingedly connected to its respective component and apertured to dispense paper from the compartment for use in conjunction with powder dispensed from the powder-compartment, and a mirror in one of said components in juxtaposition to the powder-compartment and associated with one of said closures when the container is closed. 115 120 125

In testimony whereof we affix our signatures.

WILLIAM H. CANNARD.

ALEXANDER W. WITBRO.
